FOLDABLE STAND FOR A MUSICAL INSTRUMENT

Ralph C. Kester, Jr., 1531 20th Ave. N.,
Lake Worth, Fla. 33460

Filed July 30, 1973, Ser. No. 383,801

Term of patent 14 years

Int. Cl. D17—99; XD6—99
U.S. Cl. D56—1 E

Fig. 1

Fig. 2

Fig. 3

Fig. 6

FIG. 1 is a perspective view of a foldable stand for a musical instrument embodying the present design, showing the stand in its unfolded position;

FIG. 2 is a side elevational view of the stand shown in FIG. 1;

FIG. 3 is a top plan view of the stand shown in FIGS. 1 and 2;

FIG. 4 is a front elevational view of the stand shown in the preceding figures;

FIG. 5 is a rear elevational view; and

FIG. 6 is a perspective view of the stand in its folded position.

I claim:

The ornamental design for a foldable stand for a musical instrument, substantially as shown.
